(57) **CLAIM**

The ornamental design for a motor-driven compressor, as described in the foregoing specification and the accompanying figures.

DESCRIPTION

FIG. 1 is a front view of a motor-driven compressor for a vehicle air conditioner, according to the design of the present invention.

FIG. 2 is a rear view of the motor-driven compressor shown in FIG. 1.

FIG. 3 is a left side view of the motor-driven compressor shown in FIG.1.

FIG. 4 is a right side view of the motor-driven compressor shown in FIG. 1.

FIG. 5 is a top view of the motor-driven compressor shown in FIG. 1.

FIG. 6 is a bottom view of the motor-driven compressor shown in FIG. 1.

FIG. 7 is a left side perspective view of the motor-driven compressor shown in FIG. 1; and,

FIG. 8 a right side perspective view of the motor-driven compressor shown in FIG. 1.
